OPHTHALMIC MOUNTING

Raymond L. Wells, Attleboro, Mass.

Application February 16, 1934, Serial No. 711,516

1 Claim. (Cl. 88—44)

This invention relates to ophthalmic mountings and more particularly to the folding type of such mountings.

A principal object of the invention is to provide improved means by which such a mounting may be compactly folded to occupy a small space.

Another important object of the invention is to provide improved means for attaching the guards whereby the guards may be adjusted as to their distance apart and as to their height.

Another object is to provide improved means for securing the rims.

Other objects are to provide improved locking means for holding the lenses securely in folded position, to provide improved means for hinging the bridge member and for holding the same in alignment.

Other objects and advantages will become apparent from the following description taken in connection with the accompanying drawing. It is apparent that many changes may be made in the details of construction and arrangement of parts without departing from the invention as expressed in the accompanying claim. I therefore do not wish to be limited to the exact arrangements shown and described as the preferred forms only have been shown by way of illustration.

30 Referring to the drawing:

Fig. I is a perspective view showing an ophthalmic mounting embodying the invention folded in place in a small receptacle.

Fig. II is a front elevation showing an ophthalmic mounting embodying the invention in open or usable position.

Fig. III is a top view of the left hand half of Fig. II, with the parts extended for use.

Fig. IV is a top view showing the parts, partially folded, the two lenses being aligned and parallel with each other.

Fig. V is an enlarged longitudinal section through a portion of the bridge and a lens rim showing the pivotal connection of the bridge and the lock for the same.

Fig. VI is a cross section on line VI—VI of Fig. V, showing the lock of the bridge connection.

Fig. VII is a perspective enlarged view of the rim and guard connections, the parts being shown aligned but unconnected, and

Fig. VIII is a cross section through the handle and retaining lock.

Referring to the drawing, in which like reference characters indicate like parts throughout,

I mount a pair of lenses 1, Fig. II, in the lens rims or lens holding means 2. The rims are split or divided at 3 and provided with the foot piece 4, and the abutment 5, Fig. VII. The parts 4 and 5 are arranged to abut and lie against each other. The part 4 is made as a hollow box with the open end 6. A screw opening 7 extends through the part 4. The part 5 is provided with the threaded screw receiving opening 8 extending thereinto.

I provide a guard supporting plate 9, being a bent plate having the portions 10 and 11 at an angle to each other. The portion 10 has a plurality of screw holes 12, and the portion 11 the screw hole 13. The holes 12 and 13 are threaded for a purpose described later. The plate 9 is constructed so that either the part 10 or the part 11 may be placed in the hollow box of the part 4 through the opening 6. A nose guard plate 14 having the bearing parts 15 and 16 is provided with a channel box 17 adapted to receive either the portion 10 or the portion 11, as desired, of the plate 9. The screw hole 18 extends through the plate 14 into the channel box 17 and is adapted to align with the holes in the plate 9.

If the part 11 of the plate 9 is on the upper side it is clear that the guard plate 14 will be up higher when the part 11 is secured in the box 17 than it would be if the part 11 was on the under side as indicated by dotted lines. Also, it is clear that if the part 10 of the plate 9 were secured in the box 17, the part 10 being on the upper side, and the uppermost hole 12 used to secure it in place, the guard plate 14 will be raised considerably higher than if the part 11 were used, and vice versa, much lower down if the part 10 were on the under side and the lower hole used for securing it in place in the box 17. This arrangement provides means for placing the guard plate 14 at various heights up and down.

If the plate 10 is inserted in the box of the part 4 and the outermost hole 12 used to secure the parts together, the guard plates 14 will be much nearer each other than if the portion of part 10 containing the outermost hole 12 were cut off and the innermost hole 12 used to secure the said parts. In this way means are provided for placing the guard plates 14 at different distances between them.

The guards and rims are secured together by placing one end of the plate 9 in the box of part 4 and the other end in the box 17 of the part 14, as described, aligning the screw holes of the parts and tightening the screw 19 in the holes 7 and 8.

of the parts 4 and 5 and the screw 20 through the hole 18 in the part 14 and the desired opening or hole in the plate 9. The parts may be taken apart by withdrawing the screws 19 and 20. It 5 is clear that various forms of guard plates 14 may be used, as desired, and that various sizes of plates 9 may also be used to obtain desired heights and distances between the guard plates 14.

10 A novel feature of the invention is to provide the plates 9 with extensions which may be cut off in order to make desired adjustments of the guard plates 14 following the principle described above.

15 The position of the point 3 of the rim connection may be varied if desired, and either a rimmed or rimless form of lens connection may be used, as usual in the prior art. The abutment 5 may be an offset foot like the part 4 also, if desired, 20 as is usual in the prior art. Various forms of prior art guards or guard pads may be also used as required or desired.

The lenses are connected by the bridge member 21. This bridge is preferably made of resilient, springy sheet spring material which may be flexed in the vertical plane but resistant to flexing in the horizontal plane due to its width. By flexing the bridge in the vertical plane the guards may be separated from each other to permit them 30 to be placed on the nose, and when released the spring of the bridge will hold the guards against the nose and hold the mounting in place thereon in the usual manner of spring bridge mountings. Each lens holding member is provided with a 35 bridge connecting abutment 22. Adjacent each end the bridge 21 is provided with a pivot connection 23, Fig. V and Fig. VI, pivotally securing the bridge to the abutment 22. The underside of the bridge end is channeled or recessed as at 40 24, and the abutment is recessed at 25, the two recesses being aligned. The abutment 22 is constructed as a hollow box. Within the box of the abutment 22 is pivoted at 26 the keeper or lock member 27 having an end projecting through the 45 openings or recesses 24 and 25. The keeper or lock 27 is resiliently urged to extend through the recesses 24 and 25 by the blade spring 28, having one end engaging the inner walls of the box of the abutment 22 and the other the keeper or lock 27. 50 The outer end of the keeper 27 is bevelled as at 29, Fig. VI. This bevelled face acts as a cam surface to operate the keeper when the bridge 21 is rotated on its pivot 23. Referring to Fig. VI, if the bridge portion 21 is moved towards the 55 left, the edge of the opening 24 on the right hand side will push against the bevel or cam face 29 of the keeper and push it downward out of the way, thus allowing the bridge end to move towards the left. If, however, the bridge end were 60 moved towards the right, the edge of the channel 24 would bear against the solid shoulder or face 30 of the keeper and would be prevented from movement in that direction. The spring keeper keeps the bridge and abutments resiliently aligned 65 when the mounting is extended for use.

Referring to Fig. IV, it will be noted that the left hand lens of Fig. II has retained its original position. It has been held in the left hand and prevented from movement. The right hand lens 70 has been drawn forward by the right hand and at the same time has been drawn around in front of the left hand lens to a position separated therefrom but parallel and aligned therewith. From the position shown in Fig. IV, the right hand lens may be pushed against the left hand 75

one, so that they lie snugly fitted together as shown in Fig. I. This action is due to the pivots 23 of the bridge and the action of the keepers 27. At each of the pivots 23 the bridge can only move in one direction as described above, which 5 permits the folding operation described. When the two lenses lie snugly against each other, the back of the right hand lens fitting over the front of the left hand one, the bridge lies snugly on top of the rims, extending from abutment 22 to 10 abutment 22 in substantially a horizontal plane across the top of the lenses, see Fig. I. With this pivoting the two lenses are laid compactly against each other and the whole structure occupies a minimum of space, and the guards do not interfere with each other, as one is on the right hand side and the other is on the left. The whole thing fits as snugly together as the two unmounted lenses would fit if laid one on the other. The mounting parts do not interfere with each other, 15 which is a unique and novel feature of this invention.

If desired, a handle and ribbon connection 31, Fig. II, may be provided. A lock 32, Fig. VIII, may also be provided to lock the two lenses together when folded. The lock 32 has the notch 33 and cam face 34. The lock 32 extends through the opening 35 in the handle 31. Mounted in the handle 35 is the plunger 36 pressed by the spring 37 and movable by the finger catch 38. The 30 plunger 36 has the cam face 39 which engages the cam face of the lock keeper 32. When the handle is fitted over the lock keeper 32 the plunger 36 is forced back by the cam faces of the plunger and lock keeper until the plunger slips under the 35 head of the notch 33, thus locking the parts together. To release the plunger the finger catch 38 is pushed back, drawing the plunger out of the notch 33, when the parts may be released.

When folded together, the mounting may be 40 placed in a very small receptacle or case 40, small enough to fit easily in a man's vest pocket. It may be encased in a receptacle as small as 2 1/8 x 1 7/8 x 3/4 inches outside dimensions, occupying about half the space of a man's vest pocket. 45 It may also be placed in small, highly ornamented or jeweled cases suitable for ladies' hand bags, etc. Likewise, it may be easily carried without a case in the pocket, hand bag, or suspended on a chain or ribbon. It is so compactly fitted together and locked in such a small space that it 50 may be easily and safely handled and stored away. Attention is directed to the fact that the bridge member 21 is not twisted from its normal set when the lenses are in folded position and 55 for this reason there is no bending introduced which, in devices of this nature in the past, caused strain which distorted the bridge and changed the relation of the parts.

Another outstanding feature of applicant's 60 invention is that it permits the use of lenses having odd shaped contours and allows the said lenses to be snugly and compactly fitted with each other, causing the contours to be matched with each other when the lenses are in folded 65 relation.

Its snugness of fit, compactness, and smallness of size are novel and unique features of the invention. Due to these features, it lends itself to treatment as an article of jewelry, both in 70 precious material and ornamentation of the mounting and its casing.

Attention is directed to the fact that although the plate 9 described above is shown as having only two openings 12 in its portion 10 and one 75

opening 13 in its portion 11, the said portions 10 and 11 may be formed to any lengths desired and may be provided with any desired number of openings. The said portion 9 may be made of resilient, rigid or ductile material, or different portions thereof may have one or more of these characteristics. The use of screw type connecting means obviates the heating and possible softening of the part 9, such as would be the case if the parts were united by solder. The part 9 may be so constructed that, in addition to its permitting predetermined adjustments of the nose guards, as described above, the said part 9 may be altered by bending after the parts are assembled. This permits the forming of slight adjustments.

From the foregoing description of the construction and operation of the invention, it will be seen that novel, simple, and efficient means have been provided to obtain all the advantages and objects of the invention.

Having described my invention, I claim:

An ophthalmic mounting comprising two lens members, a bridge above the lens members connecting the lens members, the ends of the bridge being pivoted to the upper portions of the lens members about axes substantially parallel to the plane of the lens members, each lens member being freely pivotally movable about its axis in one direction into substantial alinement with the bridge and also in the opposite direction out of alinement with the bridge, whereby the lens members may be caused to pivot out of the said substantial alinement in the said opposite direction to approach each other sidewise in substantially the form of a Z until the back of one lens member lies substantially against the front of the other lens member, and inter-engaging lock means provided on the lens members for locking the lens members together one over the other.

20

RAYMOND L. WELLS.
